UNITED STATES PATENT OFFICE.

ROYAL L. COLBY, OF ALEXANDRIA, MINNESOTA.

CAR-DOOR.

SPECIFICATION forming part of Letters Patent No. 613,495, dated November 1, 1898.

Application filed March 26, 1898. Serial No. 675,248. (No model.)

To all whom it may concern:

Be it known that I, ROYAL L. COLBY, a citizen of the United States, residing at Alexandria, in the county of Douglas and State of Minnesota, have invented certain new and useful Improvements in Car-Doors; and I do hereby declare the following to be a full, clear, and exact description of the invention, such as will enable others skilled in the art to which it applies to make and use the same.

This invention relates to freight-car doors, and more especially to that class adapted to cars intended to convey grain and the like. These doors are usually applied to the inside of the car-door opening, at the lower portion thereof, to prevent the escape of the grain from the side and bottom edges of the ordinary freight-car door. Doors of this character have been made, I am aware, with provision for throwing the door tightly against the door-jambs when locked for the purpose of preventing the escape of the grain at the sides thereof.

It is the object of my invention to provide a grain-car door with simple means, capable of ready and easy operation, for locking the door in place, which means shall perform the dual function of forcibly pressing the door tightly to its seat both against the jambs and the sill, and thus effectually prevent escape of grain or the like at any point.

A further object is to arrange such means at different points on the door, so that it will be rigidly held in position at all points.

A further object is to provide the door with a plurality of locking-bolts, preferably one at or near each of the four corners thereof, and a single operating means for throwing all of the bolts simultaneously.

A further object is to generally improve and simplify the construction and arrangement of such locking-bolts and their operating means.

With such objects in view my invention is embodied in the parts, arrangement, and combinations thereof, to be hereinafter described, and particularly set forth in the claims.

In order that my invention may be better understood, I have shown in the accompanying drawings a practical embodiment thereof, but desire it to be understood that I do not

limit myself to the exact construction which I have therein, for the sake of illustration, delineated.

In the drawings, Figure 1 is a front elevation of a door, showing my improvement applied thereto. Fig. 2 is a vertical sectional view on line 2 2 of Fig. 1, showing the door in elevation. Figs. 3 and 4 are end and inside elevations of the bolt-keeper, and Figs. 5 and 6 are end and side elevations of the bolt.

Referring to the drawings, wherein like reference characters refer to similar parts throughout the several views, A represents a grain-car door which, as is usual in such doors, covers but the lower portion of the door-opening. This door may be provided with suitable supporting-brackets a, slidably engaging vertical rods B, secured at the sides of the door-opening to the car side and provided near their upper ends with shoulders b, with which said brackets a are adapted to engage when the door is slid vertically upward and on which the door may be turned when raised up into the position shown in the dotted lines in Fig. 2 and there secured out of the way by any preferred means, as a hook b, depending from the car-roof. The parts above described are common in grain-car doors and form no part of my invention, and other means for accomplishing the same result may be employed.

Slidably mounted in brackets 1, preferably arranged one at or near each corner of the door, are bolts 2, adapted to be thrown into engagement with metallic keepers 3, arranged in suitable relation thereto on the door-jambs. These bolts and keepers are of novel construction to be hereinafter described. For throwing these bolts simultaneously I pivot on four bolts 4, one adjacent to each of the bolts 2, four short levers 5. At one end each of the two levers 5 at one end of the door is pivotally connected to a rod 6, and one end of each of the two levers 5 at the opposite end of the door is pivotally connected to a similar rod 6^a. One of these rods 6 and 6^a is pivotally connected at its end opposite its connection with the levers 5 with a lever 7 on one side of its fulcrum 7^a, and the other of the levers 6 and 6^a is pivotally connected to the lever 7.

on the other side of its fulcrum. By this construction it will be seen that by turning the lever 7 on its fulcrum the rods 6 6^a will be moved in opposite directions and will turn the levers 5 upon their pivots 4, thus throwing the bolts 2 into or withdrawing them from their keepers, according to the direction of the movement of the lever 7. It will be readily understood that if the bolts 2 have a some-
 what loose engagement in their brackets 1 they need simply to be pivoted to their operating-levers 5 and will have sufficient lateral play to permit of the operation of the levers; but as my bolt and keeper are of peculiar construc-
 tion I desire that the bolt should always be held in proper relation to the keeper, and for this purpose I give each bolt a rather extended bearing in its bracket 1, so that it has practically no lateral movement, and provide each operating-lever 5 with a slot 4^b, into which the pivotal connections between the bolts and the levers slidably engage. The levers 5 are similarly slotted at their opposite ends at 5^b to afford a sliding engagement for the pivotal connection between them and the levers 6 and 6^a. To insure a perfect adjustment of the parts and to permit the bolts to be thrown a greater or less distance to properly seat them in or attract them from the keepers, I have shown each of the rods 6 and 6^a provided with a series of bolt-holes 6^b, into any one of which the pivot-connecting bolt between the lever 7 and the rod 6 or 6^a may be inserted.
 To hold the parts in their locked or unlocked position, a rack 8 is secured to the door, with the teeth of which a projection 8^a on the lever 7 is adapted to engage. Any suitable means, however, may be provided for locking the lever in its different positions. Referring especially to Figs. 3 to 6, it will be seen that the bolt 2 is provided at its outward end, or that end which engages the keeper, with an inclined surface 2^a on its top and on its outer side or side away from the door with an inwardly-inclined surface 2^b, and its keeper 3 is likewise provided with a downwardly-inclined surface 3^a on the under side of its top, with which the inclined surface 2^a of the bolt is adapted to engage, and with an inwardly-inclined surface 3^b on its side, with which the inclined surface 2^b of the bolt is adapted to engage. On account of the relative arrangement of these inclined surfaces of the keeper and bolt it will be seen from Fig. 1 that when the bolt is moved longitudinally the engagement of the inclined surfaces 2^a and 3^a will tend to force the bolt inward and downward. As the bolts are arranged at the four corners of the door and secured thereto, the described inclination of each of the bolts to move downward and inward will cause the door to be firmly thrown downwardly against the sill and inwardly

against the door-jambs, forming a perfectly 65 tight joint between the door and its casing.

The arrangement of the bolts relative to their keepers is such that when the inclined surfaces of either or both become worn it is simply necessary to throw the bolts farther 70 into the keepers and they will have the same effect, and this additional movement of the bolts can be readily accomplished with the same throw of the lever 7 by adjusting the pivot-connecting bolts of the lever 7 into the 75 proper aperture 6^b in the levers 6 and 6^a.

If the door A should be let into seats in the jambs instead of being placed against the outside surfaces thereof, as shown, so that the face of the door would be flush with the face 80 of the jambs, it will be necessary to provide recesses or notches 9 in the jambs opposite the bolts to permit of the proper inward movement of the bolts when thrown.

Having thus described my invention, what 85 I claim as new, and desire to secure by Letters Patent, is—

1. The combination with a grain-car door, of means for moving the door downwardly to its sill and inwardly to its jambs, comprising 90 a bolt at each end of the door; metallic keepers on the jambs provided with outwardly-extending portions each having a double inclined surface, and means for throwing said bolts.

2. The combination with a grain-car door, of four bolts slidably mounted thereon, one at or near each corner, four levers each pivoted to the door and one pivotally attached to each bolt, a rod pivotally secured to the 100 adjacent ends of two levers at one side of the door, a second rod pivotally secured to the adjacent ends of the two levers at the opposite side of the door, a hand-lever pivoted to the door and pivotally connected to each of 105 said rods, means for holding said lever in different positions, and keepers for the bolts.

3. The combination with a grain-car door, of a hand-lever pivoted thereon, four bolts slidably mounted on said door, one at or near 110 each corner thereof, a separate means for throwing each bolt, two rods connected to said hand-lever, each of said rods being operatively connected to two of said bolt-throwing means, and keepers for the bolts.

4. The combination with a grain-car door, of bolts, one at each side thereof, a lever 5 for each of said bolts, a hand-lever pivoted to the door, rods pivoted to each of said levers 5 and adjustably connected to the hand-lever, means for holding said hand-lever in different positions and keepers for said bolts.

In testimony whereof I affix my signature in presence of two witnesses.
